CLAIM

I claim the ornamental design for the watch case, as shown and described.

DESCRIPTION

FIG. 1 is a top perspective view of the new ornamental watch case of the present invention.

FIG. 2 is a left side view thereof wherein the watch case is inverted.

FIG. 3 is a bottom view of the watch case.

FIG. 4 is a rear view thereof.

FIG. 5 is a right side view thereof.

FIG. 6 is a front view thereof; and,

FIG. 7 is a top view thereof.
